UNITED STATES PATENT OFFICE.

SAMUEL SMILEY, JR., OF CINCINNATI, OHIO, ASSIGNOR TO THE GLOBE-WERNICKE COMPANY, OF CINCINNATI, OHIO, A CORPORATION OF OHIO.

LOOSE-SHEET BINDER.

Application filed March 14, 1923. Serial No. 625,103.

To all whom it may concern:

Be it known that I, SAMUEL SMILEY, Jr., a citizen of the United States, and residing at Cincinnati, in the county of Hamilton and State of Ohio, have invented a new and useful Improvement in Loose-Sheet Binders, of which the following specification is a full disclosure.

This invention relates generally to loose sheet filing or temporary-binder devices and particularly to the bendable prong type, in which the prongs are fixed to a suitable base and for securing the sheets, which prongs are engaged through the apertures in the sheets with the end portions thereof projecting beyond the bound sheets, and bent at an angle upon the sheets.

One of the objects of the invention is to provide a plate cleat for reinforcing the body portion of a bendable prong binder element and for substantially securing the binder element to a flexible paper board base as to a leaf of a folder.

Another object of the invention is to provide means for preventing wear or puncture of the folder material due to frequent bending of the sheet-attaching tangs or prongs to clasp the sheets after they have been bound, this object being accomplished by passing the bendable tangs or prongs from one side of the base or folder leaf through the folder leaf and through a cleat on the opposite side of the folder leaf or base, whereby any friction at the bending points of the prongs between such points and the folder material is prevented.

Other objects and certain advantages will be more fully set forth in the description of the accompanying drawings, forming a part of this application, in which:

Figure 1 is an inner face view of the open folder or cover showing a preferred form of reinforcing member or cleat and sheet binder element.

Figure 2 is an enlarged detail plan of structure of Figure 1, a portion of the upper reinforcing member and folder sheet being broken away to show the body or connecting portion of the bendable prongs.

Figure 3 is a section on line 3—3 of Figure 2, showing the manner of interlocking the elements.

Figure 4 is a section similar to Fig. 3, showing a device in use, a follower or clamp-

ing plate being engaged with the upper sheet 55 of the pile.

Figure 5 is a plan view of a modified form.

Figure 6 is a section on line 6—6 of Figure 5.

Figure 7 is a view similar to Fig. 2, showing a modified form of sheet retaining element.

Figure 8 is a detail end view showing the prong retaining device.

The binder comprises two elements attached in opposition to one another at relatively opposite sides of a base 1, the base being in the form of a folder or cover for enclosing and protecting the bound sheets. 70 The bendable binder and base reinforcing cleat elements are preferably formed from sheet metal and are respectively designated by the numerals 2, 3. The bendable binder element 2 comprises a strip of metal formed 75 with an elongated rectangular body portion having spaced openings 4 for the reception of suitable fastening means, such as rivets or eyelets for securing the parts of the device to the cover or folder leaf, and prongs or tangs 5 extending from the opposite ends of the body portion, of less width than the body portion, said tangs adapted to be passed through the paper and through openings in a cleat element 3. The element 3 is also of 85 elongated rectangular configuration, is of greater length than the body portion of the element 2, and has therein openings 4^a spaced to correspond to the openings 4 of the element 2. Transverse openings in the form of 90 elongated slots 7 are provided at relatively opposite ends of the element adjacent said openings 4^a and between the ends thereof and said openings. In attaching the device, the element 2 is placed at one side of the 95 base, and its prongs, preferably bent at a right angle to the body portion, are passed through the base or folder leaf. The slots 7 of the element 3 are then each engaged over a respective upstanding prong and the elements slid to contact the base on the side thereof opposite that of the element 2, after which the rivets are passed through the registering openings 4 and 4^a and turned to fasten the elements securely together. With 100 the tangs passing through a metal reinforcing plate or cleat, subsequent frequent bending of said tangs, when placing the sheets

or removing the same, will not tear the folder sheet, such wear being, in this, instance, against the sides of the slots 7.

As shown in Fig. 4, the record or cor-

respondence sheets 10 are preferably pro-
vided with openings 11 adapting the sheets
to be conveniently engaged over the prongs
when said prongs are in upstanding position.
A follower or clamp element 12, preferably
10 of metal, having suitable prong receiving
openings therein clampingly sustains the
papers, the tangs traversing the openings
in the follower element and being bent out-
wardly and downwardly thereagainst. The
15 extremities of the prongs may be retained
by transverse prong holding devices, indi-
cated at 15, beneath which the ends of the
prongs are finally inserted.

In the form of device shown in Figures
20 5 and 6, the tangs of the element 2 do not
traverse the folder sheet or companion ele-
ment 3, the element 2 being placed at the
inner side of the sheet and the element 3 at
the outer side. The ends of the element 3
25 project outwardly beyond the bends 16 of
the prongs and act as a backing for the
material of the folder, when said prongs are
bent downwardly, supporting the paper at
these points and preventing undue wearing
30 or tearing of the same. The elements are
secured by rivets or other suitable devices
in a manner similar to that heretofore de-
scribed.

In Figure 7 the element 2 is formed from
35 a narrow strip of single dimensioned width
cut to the desired length with a portion of
the opposite ends providing the prongs or
tangs 5^a preferably pointed, and the inter-
mediate portion is provided with spaced
40 openings 4^b for registration with the open-
ings 4 of the cleat element 3^a, the strip in
providing the apertures or openings being
spread or expanded. The element 3^a is iden-
tical in form with the element 3 and the ele-
45 ments are preferably attached to the sheet as
in the first form. By reinforcing the mate-
rial of the folder or cover at each side about
the points of attachment of the binder de-
vice, the life of the folder is materially in-
50 creased. By passing the prongs of one ele-
ment through the opposing element, the
paper is further protected from injury when
the prongs are bent back and forth as when
attaching and detaching the sheets. The
55 material of the folder is also protected
against undue injury by extending one ele-
ment beyond the other to back or reinforce
the material of the cover adjacent the bend-
ing points of the tangs, as illustrated in Fig-
ures 5 and 6.

Having described my invention, I claim:

1. In a device of the class described, in
combination with a foldable sheet, a tang-
carrying member having the tangs thereof
projected through the sheet, a second mem-

ber at the opposite side of the sheet and
traversed by said tangs, and means for
clampingly fastening said members to-
gether.

2. In a device of the class described, in
combination with a foldable sheet, a tang-
carrying element having tangs bent at right
angles thereto, a second element of greater
length than said tang-carrying element
75 placed in opposition to said tang-carrying
element at the opposite side of said sheet,
and means for clampingly fastening the ele-
ments together.

3. In a device of the class described, in
combination with a sheet, members located
upon opposite sides of said sheet, means for
securing said members to each other, prongs
carried by one of said members projecting at
right angles thereto and adapted to traverse
80 a plurality of sheets, a member with open-
ings spaced to receive said prongs and adapt-
ed to clamp a plurality of sheets to the first
specified sheet and transverse prong retain-
ing members on the last specified member.

4. In a device of the class described, in
combination with a foldable sheet, a tang-
carrying element having tangs bent at right
angles thereto, a second element of greater
length than said tang-carrying element
95 placed in opposition thereto at the opposite
side of said sheet with respective ends pro-
jecting beyond the corresponding ends of
said tang-carrying element, and means for
clampingly fastening the elements together.

5. In a device of the class described, in
combination with a foldable sheet, an ele-
ment having integral tangs bent at right
angles thereto, said tangs passed through
said sheet, a second element having spaced
100 transverse slots therein, said slots engaged
over said tangs, said second element en-
gaged against said sheet in opposition to
said tang-carrying element, and means for
securing said elements together.

6. In a device of the class described, in
combination with a foldable sheet, an ele-
ment having integral tangs at opposite ends
bent at right angles to said element, said
element engaging said sheet at one side, a
115 second element of greater length than said
first-mentioned element placed in opposition
thereto, on the opposite side of said sheet
and having its ends projecting beyond the
bending points of said tangs.

7. In a device of the class described, in
combination with a sheet of material, an ele-
ment having bendable tangs thereon, said
tangs bent at right angles to said element
and inserted through said sheet, a second
element having openings registerable with
120 the points of said right angularly bent
tangs, said second element adapted to be
engaged over said tangs to lie at the oppo-
site side of said sheet in opposition to said
first-mentioned element, and means for
125

clampingly securing said elements together.

8. In a device of the class described, in combination with a sheet, members on opposite sides of said sheet, means for clamping said members together, prongs carried by one of said members projecting at an angle thereto.

In witness whereof, I hereunto subscribe my name, as attested by the two subscribing witnesses.

SAMUEL SMILEY, JR.
